CHARLES M. WIZEK, OF CLEVELAND, OHIO

WINDOW LOCK AND FASTENER

Application filed March 5, 1931. Serial No. 520,329.

My invention relates to window locks and fasteners, and in general my object is to provide an efficient locking and fastening device of such simple construction that it may be produced at a low cost and also easily attached to a window sash and conveniently operated, all as hereinafter shown and described in greater detail and more concisely set forth in the claims.

10 In the accompanying drawings, Fig. 1 is a perspective view of a portion of a window and my improved fastening device mounted thereon. Fig. 2 is a sectional view of the device assembled, and Figs. 3, 4, and 5, are 15 perspective views of the three pieces comprising the working structure.

The invention comprises a window lock or fastener made in three parts or pieces, a substantially Z shaped base member A, a U-shaped clamping member or slide B, and a thumb screw C. Base member A and clamping member B are stamped or folded from flat strip metal into their respective angular forms. Thus, base member A consists of a 25 flat strip of metal folded at right angles on parallel lines, transversely thereof to provide a base flange 2, a vertical wall 3, and a forwardly projecting top flange 4. Base flange 2 is provided with countersunk screw-openings 5 to permit this member A to be secured rigidly in an upright position upon the upper rail 6 of a window sash D opposite the stile 7 of a second sash E. The vertical wall 3 in member A is formed with a flanged opening 8 which is screw-threaded to receive thumb screw C, one end of which is provided with a flattened thumb-engaging portion or handle 9. The opposite end of screw C has a reduced extension 10 which passes through a flanged opening 11 in the vertical wall 12 of the clamping member or slide B to provide a rotatable or swiveled connection therefor when the outer end of this reduced extension is upset. The stock around opening 11 is flanged inwardly to provide a countersunk

recess or cavity 14 wherein the enlargement 15 on the outer end of the screw may be seated in a retired position in respect to the flat vertical clamping face 16 of slide member B, thereby preventing injury or marring of the 50 stile on window sash E when the screw is rotated and slide member B is pressed tightly against the stile.

Slide member B is confined upon the upper rail 6 of lower sash D by the overhanging 55 flange 4 of stationary member A, but is free to slide back and forth in respect to the upper sash when operated by screw C. Members A and B being made of flat bendable metal, for example, spring brass, a certain measure 60 or degree of flexibility or spring exists inherently in the structure, whereby the clamping strain on the device and on the attachment screws is relieved under extreme stress. Also when the locking member B is clamped 65 against the upper sash by the pressure of the screw the tendency of the device is to jamb more tightly against the upper sash with spring locking effect. The screw is also located above the horizontal medial line in the 70 device to slightly accent such results and to elevate the thumb piece sufficiently in respect to the base flange end sash so that the screw may be rotated freely by the thumb and fingers without interference with the base flange 75 and sash.

What I claim is:

1. As an article of manufacture and sale, a window lock or fastening device, comprising a base member made of flat spring metal folded at right angles to provide a base flange, a vertical wall adjoining said base flange, and an overhanging flange extending from said vertical wall; a clamping member slidably engaged with said overhanging flange; and a 85 clamping screw extending through the said vertical wall having swivel connection with said clamping member.

2. As an article of manufacture and sale, a window lock or fastening device, comprising 90

a base member made of flat spring metal folded into **Z** shape having its vertical wall provided with a screw-threaded opening in its upper portion; a clamping member made of flat stock folded into substantial **U**-shape; and a clamping screw extending through said opening in said base member, having rotatable connection with the upper portion of the web of said clamping member.

10 In testimony whereof I affix my signature.

CHARLES M. WIZEK.
